UNITED STATES PATENT OFFICE.

HAROLD A. DENMIRE, OF AKRON, OHIO, ASSIGNOR TO THE B. F. GOODRICH COMPANY, OF NEW YORK, N. Y., A CORPORATION OF NEW YORK.

THREAD-GUIDE FOR BALL-WINDERS.

1,391,247.

Specification of Letters Patent. Patented Sept. 20, 1921.

Application filed November 21, 1918. Serial No. 263,507.

To all whom it may concern:

Be it known that I, HAROLD A. DENMIRE, a citizen of the United States, residing at Akron, in the county of Summit and State 5 of Ohio, have invented a certain new and useful Thread-Guide for Ball-Winders, of which the following is a specification.

This invention relates to winding or wrapping machines, and more especially machines 10 for forming the centers of golf balls with rubber thread or tape. My object is to provide an improved thread-guiding and tensioning means which will reduce the amount of breakage of the thread in passing from 15 the spool to the ball. It has heretofore been a common practice in machines of this type to lead the rubber thread from the spool directly over the tension roller, which can be a grooved roller provided with a brake and 20 rotating in a plane at right-angles to the plane of rotation of the spool upon its own axis, but is more commonly an elongated roller parallel to the spool, over which the thread shifts in assuming various angles ac- 25 cording to the place on the spool from which it is unwinding. The breakage, which has been observed to be due to a kinking of the rubber thread or tape or an uneven tension thereon in certain rotative positions of the 30 winding ring which carries the spool is largely overcome by means of the expedient hereinafter described.

Of the accompanying drawings,

Figure 1 is a front elevation showing the 35 principal working parts of a ball-winding machine provided with my improvement.

Fig. 2 is a section on the line 2-2 of Fig. 1.

Referring to the drawings, 10 is the base 40 of the machine on which is mounted a circular track 11 supporting the ring winder 12 which rotates on a ball-bearing 13, the winder having gear teeth 14 formed on its periphery whereby it is driven from a driving gear 15. 16 is the spool or reel having a suitable retarding brake 17, and 18 is the narrow rubber tape unwound therefrom, which, for present purposes, may be termed the "thread". The spool shaft is mounted in 45 bearing brackets 19 on one side of the winder ring and these parts are counter-balanced by a weight 20 affixed to said ring at an opposite point on the circumference thereof. On the bar 21 on said ring are mounted the 50 several guide rollers, as well as the slotted

needle 22 which maintains the thread in the winding plane.

The holder for the ball 23 is in the usual form of two pairs of parallel rollers 24 which are driven by suitable mechanism imparting thereto an intermittent rotary motion to turn the ball on a horizontal axis, and are mounted in bearings on a pair of heads 25 reciprocated horizontally in opposite directions to rotate the ball on a vertical axis.

26 is a tension roller fixed to a shaft 27 whose axis is parallel to that of the thread spool 16, this shaft having one bearing in an arm 28 on the bar 21 and another bearing in one of the brackets 19, the shaft 27 having a friction plate or brake 29 provided with a spring adjustment 30 whereby a variable drag is imposed upon the tension roller. Heretofore, the thread has passed 75 directly from the spool 16 to a tension roller on the same side of the winder ring, and said roller has commonly been located as shown in my drawings but made of elongated form to permit the travel thereover of the thread 80 in different angular positions assumed by the latter. This arrangement resulted in the kinking and breakage of the rubber thread heretofore mentioned. According to the herein-described preferred embodiment of 85 my invention which allows the improvement to be readily adapted to existing machines, I introduce an idle roller 31 for guiding the thread between the spool 16 and the tension roller 26, and preferably locate it to one 90 side of said spool and tension roller, on the opposite side of the middle plane of the ring 12 from the side on which those members are mounted. This idle roller is located nearly on a diametric plane bisecting the spool 16 and rotates in a plane at right-angles to the plane of rotation of the spool on the latter's own axis, so that as the thread changes its angle in feeding from said spool to the roller 31 it merely wraps more or less around said 95 roller, and does not affect the angular direction of the part of said thread leading from the roller 31 to the tension roller 26. Thus the tension remains substantially uniform at all times, and the thread or tape has much 100 less tendency to kink and break than heretofore. From the tension roller 26 the thread 18 passes to the needle 22 over a loosely-journal guide roller 32 mounted on the 105 bar 21 for bringing said thread substan- 110

tially into the winding plane. The relative location of the three rolls 26, 31 and 32 causes the thread to take substantially a half-turn around the tension roller 26, and thus obtain sufficient frictional hold to rotate the latter against the resistance of its brake 29.

While the foregoing is a suitable embodiment of my invention, it is to be understood that the latter is not wholly limited to the specific number and arrangement of the members in the series of thread-guiding and tensioning rollers here shown.

I claim:

- 15 1. In a machine for winding elastic rubber thread into a ball, the combination of a holder having means for turning the ball on different axes to give a spherical winding, a rotary ring winder carrying an elongated thread spool, a guide roller on said winder mounted to rotate on an axis transverse to the axis of the spool and so positioned as to receive the thread from said spool approximately at right angles to the axis of said guide roller, but from various directions, and turn its course in a substantially fixed direction through less than a complete turn, and means on said winder for guiding the thread from said roller onto the ball.
- 20 2. In a machine for winding elastic rubber thread into a ball, the combination of a holder having means for turning the ball on different axes to give a spherical winding, a ring winder mounted to revolve about said holder, an elongated thread spool mounted on said winder on one side of the winding plane, a guide roller mounted on said winder

on the opposite side of the winding plane and rotating on an axis transverse to that of the spool, for receiving the thread from said spool, and means on said winder for guiding the thread from said roller onto the ball.

3. In a machine for winding elastic rubber thread into a ball, the combination of a holder having means for turning the ball on different axes to give a spherical winding, a ring winder mounted to revolve about said holder and carrying an elongated thread spool, a parallel tension roller provided with a brake, an intermediate thread-guiding roller mounted to rotate on an axis transverse to the axes of said spool and tension roller, and means for guiding the thread from said tension roller onto the ball.

4. In a machine for winding rubber thread on a ball, the combination of a ball-turning holder, a ring winder adapted to revolve about said holder, a thread spool and a thread tension roller mounted on said winder at one side of its middle plane and adapted to rotate on substantially parallel axes, an intermediate thread-guiding roller mounted on the opposite side of said plane and adapted to rotate on an axis transverse to the axes of the spool and tension roller, a needle for guiding the thread onto the ball, and a roller mounted on said ring winder substantially at the winding plane for guiding the thread from said intermediate roller to said needle.

In testimony whereof I have hereunto set my hand this nineteenth day of November, 1918.

HAROLD A. DENMIRE.
